OTTO JOHN GROEHN, OF GROSSE POINTE PARK, MICHIGAN, ASSIGNOR TO HUDSON MOTOR CAR COMPANY, OF DETROIT, MICHIGAN, A CORPORATION OF MICHIGAN

METHOD AND APPARATUS FOR SHAPING SHEET-METAL ARTICLES

Application filed December 10, 1927. Serial No. 239,222.

This invention relates to the formation of sheet metal articles having inset flanges, and especially, although not exclusively, to the manufacture of T-shaped moldings of the 5 type employed in the panel joints of certain metal automobile bodies.

It is an object of the present invention to provide an improved method and apparatus for shaping sheet metal articles of this type 10 rapidly and accurately wherein advantage is taken of the weakened condition of the metal along a line of previous bend to assist the subsequent shaping operations.

Before explaining the invention in detail 15 it is desired to point out that the features hereinabove described are merely for the purposes of illustration and that the invention is not thereby limited except as pointed out by the appended claims.

20 The invention will be more clearly understood from the following description in conjunction with the accompanying drawings, in which:

Fig. 1 is a plan view of an apparatus embodying the invention showing the relation 25 of the parts at the completion of the shaping operation;

Fig. 2 is an elevational view of the same;

Fig. 3 is a sectional elevational view taken 30 upon the line 3—3 of Fig. 1, showing the relation of the parts at the beginning of the final shaping operation;

Fig. 4 is a similar sectional view showing 35 the relation of the parts at the completion of the shaping operation;

Fig. 5 is a sectional elevational view of a portion of the apparatus taken upon the line 5—5 of Fig. 1;

Figs. 6, 7, 8 and 9 are detail sectional views 40 showing the successive relation of the dies and the sheet metal being shaped from the beginning to the completion of the final shaping operation.

An apparatus embodying the invention 45 comprises a base 10 provided at its opposite sides with spaced upwardly extending projections 11 forming a depression 12 therebetween. A member 14 of suitable wear resisting material is secured within the depression 50 12 and is suitably shaped to receive the body

15 of the sheet metal to be shaped. A support 16 is movably and yieldingly mounted within the depression and is provided with an opening 9 to permit its free movement toward and from the member 14. The support 16 is held normally in raised position by springs 13 extending between the supports 16 and openings 18 in the base.

Upward movement of the support 16 is limited by bolts 35 secured to the support and passing through openings 37 provided with shoulders 38 adapted to engage the heads 39 of the bolts 35. Dies 20 are movably mounted upon opposite sides of the opening 9 in the yieldable support 16 and are provided on the inner edge with a pressure pad 21 suitably shaped to engage the flanges 22 of the previously bent sheet metal and shape the same against the supporting member 14. A wear resisting block 25 is secured as by screws 5 to the outer edge of each die 20 and is adapted to engage a suitably shaped cam 26 secured as by screws 8 to the inner edge of each of the projections 11.

A reciprocable ram 28 is provided with depending blocks or plates 29 adapted to engage the top of the dies 20 when the ram is lowered and move the dies together with the supports 16 downwardly against the action of the springs 13. Plates 30 are secured in any suitable manner as by bolts 31 to the outer opposite surfaces of the support 16 and project upwardly adjacent the dies 20. An opening 32 is provided in the upper portion of each plate 30 to receive for slidable engagement therein a bolt 33 which is secured to each die 20. A spring 34 surrounding each bolt 33 extends between the outer surface of the plate 30 and a washer 6 adjustably secured in place by nuts 7 on each of the bolts 33.

In the manufacture of the molding herein selected for the purpose of illustration, from a flat blank, said blank is first bent, by any suitable means well known in the art and not requiring description herein, into the form of a channel, as shown in Fig. 6, said channel having a body 15 with substantially parallel flanges 22 extending therefrom. In the subsequent operation of the machine herein shown, the body 15 of the previously bent

sheet metal is placed upon the member 14 with the substantially parallel flanges 22 between the pressure pads 21 of the dies 20. The ram 28 is then moved downwardly to move the dies 20 downwardly together with the supports 16. During the downward movement of the dies 20, the blocks 25 engage the cams 26 thereby causing the dies 20 to be moved toward the member 14 in intersecting paths inclined to the member 14 and causing the flanges 22 of the previously bent sheet metal to bend along the line 40 of previous bend and to be brought together into engagement with the body 15 of the sheet metal. 10 This action will be understood by reference to Figs. 6-9 wherein the pressure pads 21 are shown first coming into contact with the flanges 22 to bend them along the lines 40 of previous bend and bring their free ends together. Further movement causes the flanges 22 to be pushed together and against the body 15 of the article thereby becoming bent along a line between the free ends of the flanges and the line of previous bend. It will be noted 20 that the action of the ram 28 and the cam 26 is to urge the die 20 simultaneously in two directions perpendicular to each other thereby imparting a resultant movement thereto in a direction inclined to the member 14 which 30 supports the sheet metal.

I claim:

1. In an apparatus for shaping previously bent sheet metal, the combination of a member for supporting said bent metal, a die 35 movable in a path inclined to the supporting surface of said member, and means for moving said die to press the metal against said member to bend said metal along a line of previous bend and a line spaced therefrom. 40 2. In an apparatus for shaping sheet metal previously bent with a flange, the combination of a member for supporting the body of said bent metal, a die movable in a path inclined to the supporting surface of said member, means for movably supporting said die, and means for simultaneously urging said die in two directions perpendicular to each other thereby imparting a resultant movement thereto in a direction inclined to 50 said member.

3. In an apparatus for shaping sheet metal previously bent with parallel flanges, the combination of a member for supporting said folded metal, dies movable in intersecting paths inclined to said member, and means for moving said dies to bend the flanges along the lines of previous bend and bring the same together and press said metal against said member.

60 4. In an apparatus for shaping previously bent sheet metal, the combination of a member for supporting said bent metal, a support yieldingly mounted near said member, a die member mounted on and movable with and relative to said support, means for mov-

ing said die member and support, and means for moving said die member relative to said support.

5. In an apparatus for shaping previously bent sheet metal, the combination of a base 70 having a depression, a member within the depression and spaced from one side thereof for supporting said bent metal, a movable die, a yieldable support within said depression for conveying the movable die, means for moving said die with said support, and a cam for moving said die relative to said support as it is moved with said support.

6. In an apparatus for shaping previously bent sheet metal, the combination of a member for supporting said bent metal, a support yieldingly mounted near said member, a die member mounted on and movable with and relative to said support, means for moving said die member and support, and means for moving said die member relative to said support and means for returning said die to its initial position.

7. In an apparatus for shaping previously bent sheet metal, the combination of a base 80 having a depression, a member within the depression and spaced from one side thereof for supporting said bent metal, a yieldable support within said depression, a die member mounted on and movable with and relative to said support, means for moving said die with said support, a cam for moving said die relative to said support as it is moved with said support, and a spring arranged to press said die against said cam.

8. In an apparatus for shaping sheet metal previously bent with parallel flanges, the combination of a base having a depression, a member within said depression and spaced from the sides thereof for supporting the body of said bent metal, a support yieldingly mounted within the depression on each side of said member, a die mounted on the support and movable with and relative thereto, means for moving said die and support, and means for moving said die relative to said support.

9. In an apparatus for shaping sheet metal previously bent with parallel flanges, the combination of a base having a depression, a member within said depression and spaced from the sides thereof for supporting the body of said bent metal, a support yieldingly mounted within the depression on each side of said member, a die movably mounted on each support, means for moving said die and support, and a cam for moving each die relative to said support.

10. In an apparatus for shaping sheet metal previously bent with parallel flanges, the combination of a base having a depression, a member within the depression and spaced from the sides thereof for supporting the body of the bent metal, a support movably mounted within the depression on each side of said member, springs normally hold-

ing said support in raised position, a die movably mounted on the support, a ram adapted to move said die and support against the action of said springs, a cam on the side of said depression adapted to move said die relative to said support as it is moved by said ram, and springs arranged to press said die against said cam.

11. The method of shaping sheet metal previously bent with parallel flanges which comprises supporting the body of the metal between said flanges, bending said flanges in one direction along the line of the previous bend and in the opposite direction along a line spaced from said previous line of bend to bring the same together and against the body of the metal by pressure applied to said flange along a path inclined to said body and intersecting said second line of bend.

In testimony whereof I affix my signature.
OTTO J. GROEHN.
